FOREIGN PATENT DOCUMENTS

JP D1569207 * 2/2017

Primary Examiner — Rachel A. Voorhies*Assistant Examiner* — Benjamin D. Wannemacher(74) *Attorney, Agent, or Firm* — Sang Young Han(57) **CLAIM**

The ornamental design for a regulator socket tool, as shown and described.

DESCRIPTION

FIG. 1 is a front perspective view of a regulator socket tool, showing my new design;

FIG. 2 is a top perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate the portions of the regulator socket tool, which form no part of the claimed design.

1 Claim, 9 Drawing Sheets(56)
